UNITED STATES PATENT OFFICE.

FREDERICK S. GALLAGHER, OF YONKERS, NEW YORK, ASSIGNOR TO RODGER BALLAST CAR COMPANY, OF CHICAGO ILLINOIS, A CORPORATION OF MAINE.

DOOR LOCKING AND RELEASING MECHANISM.

Application filed March 25, 1921. Serial No. 455,483.

To all whom it may concern:

Be it known that I, FREDERICK S. GALLAGHER, a citizen of the United States, residing at Yonkers, in the county of West 5 chester and State of New York, have invented certain new and useful Improvements in Door Locking and Releasing Mechanism, of which the following is a specification.

10 This invention relates to door locking and releasing mechanism particularly adapted for use in connection with railway ballast cars.

15 One object of the invention is to provide a simple, efficient and reliable door locking and releasing mechanism.

Another object is to provide a railway car with door control mechanism adapted to lock a door holding member in a door holding or supporting position and to move said member into a nonholding position in a manner to meet all of the requirements for successful commercial operation.

20 These and other objects are accomplished by means of the arrangement disclosed on the accompanying sheet of drawings, in which—

25 Figure 1 is a fragmentary side elevation of a railway ballast car embodying my invention;

Figure 2 is a fragmentary transverse sectional view of the same car; and,

30 Figure 3 is a fragmentary longitudinal sectional view of the arrangement shown in Figure 1.

The various novel features of my invention will be apparent from the following description and drawings and will be particularly pointed out in the appended claims.

35 Referring to the figures of the drawing it will be noted that I have disclosed my invention in connection with a railway car and preferably a ballast car having sides 10 (only one being shown) and a plurality of

40 floor doors 11 (only one being shown) which it will be understood, are pivotally mounted in the usual manner adjacent the center sill structure of the car. Each of the doors 11 has at its outer edge a reinforcing angle

45 member 12, to which is secured a bracket or projecting member 13 which extends laterally from the outer edge of the car and outwardly with respect to the side 10 of the car. To hold each door 11 in closed position a link

50 14 is provided which is pivotally mounted at

its upper end in a supporting member 15 preferably permanently secured to the side of the car 10 by means of rivets 16. The lower narrowed portion of the link, when in a position for holding its associated door 11 55 in closed position, passes under the projecting bracket 13, as shown in the figures of the drawing. If some means were not provided for retaining or locking the holding link 14 in a position to hold the door 11 closed, said holding means 14 might swing outwardly, thereby releasing its associated door because of jarring actions occasioned under service conditions. To prevent accidental opening of the associated door and for locking the 60 holding member 14 in door supporting position, I have provided locking means in the form of an arm 17 pivotally mounted at 18 and arranged at the outer side of the holding link 14, said handle when in locking position being retained behind an upstanding member 19 of a bracket secured to the side of the car in any approved manner. With the handle in the position shown in the figures of the drawings, it is impossible for 65 the door holding member 14 to move into a non-supporting position.

When a car is heavily loaded considerable pressure is imposed upon the link 14, and, accordingly, considerable effort is required 70 for swinging the link 14 laterally out of engagement with its locking projection 13. For the purpose of facilitating the releasing movement of the link 14, I have provided one end of the handle 17 with a cam member 75 20, which, when the handle is swung in a clockwise direction, as viewed in Figure 1, will wedge in behind the holding link 14 and more particularly between the holding link 80 and the side of the car for forcing the link 14 laterally outwardly from a supporting position to a non-supporting position, whereupon the associated door 11 is free to drop into an open position for dumping material which is in the car.

It is seen, therefore, that a combined door locking and releasing control mechanism is provided which is simple, efficient and reliable and adapted to meet the requirements for successful commercial operation.

It is my intention to cover all modifications of the invention falling within the spirit and scope of the following claims.

I claim:

1. In a railway car, the combination of a

2
door having a projecting member, a link movable into engagement with said projecting member for holding the door in closed position, and means including a handle for locking said holding means in door supporting position and a wedge member for releasing said holding means from supporting position.

5 2. In a railway car, the combination of a
10 dump door having a laterally extending projection, a link pivotally mounted at the side of the car and movable under said projection for holding the door in closed position, a pivotally mounted handle arranged outwardly with respect to said link for locking the latter in holding position, and a wedge member formed on said handle for moving the link away from said projection for releasing said dump door.

15 20 3. A railway car having a side portion and a door portion arranged to drop away from the side portion to discharge the load, a swinging member mounted upon one of said portions adapted to engage the other portion to hold the door in closed position, movable means mounted upon the side portion to extend substantially longitudinally thereof, said means being adapted to engage the swinging member to hold the same in door holding position, said means being further provided with a member movable into engagement with said swinging member to force said swinging member from door holding position.

25 35 4. A railway car having a side portion and a door portion arranged to drop away from the side portion to discharge the load, a swinging member mounted upon one of said portions adapted to engage the other portion to hold the door in closed position, movable means mounted upon the side portion to extend substantially longitudinally thereof, said means being adapted when moved in one direction to hold the swinging member in door holding position and when moved in another direction to release said swinging member from door holding position.

40 45 5. A railway car having a side portion and a door portion arranged to drop away from the side portion to discharge the load, a swinging member mounted upon one of said portions adapted to engage the other portion to hold the door in closed position, movable means mounted upon the side portion above the plane of the door and extending substantially longitudinally of the side portion, said means being adapted, when moved in one direction, to hold the swinging member in door holding position and when moved in another direction, to release

the said swinging member from door holding position.

5 6. A railway car having the usual side portions and a door portion arranged to drop away from the side portion to discharge the load, a swinging member mounted upon one of said portions adapted to engage the other portion to hold the door in closed position, a pivoted lever mounted upon the side portion, one arm thereof extending substantially longitudinally of the side and forming an operating handle for the lever, said arm engaging the swinging member to hold the latter in door holding position, the said lever being also provided with a member adapted, upon rotation of the lever, to engage the said swinging member and release it from door holding position.

10 7. A railway car provided with a hinged dumping door, a swinging link co-acting with said door and the car to hold the door in closed position, means attached to the car engaging said link in one position to lock the link in door holding position, said means having a member engaging the link upon movement of said means to release said link from door holding position.

15 8. In a railway car, a dump door, and a link attached to the car; said door being provided with means coacting with said link to swing the link out of the path of the door during the closing movement of the door, and adapted to be engaged, by the link to hold the door in closed position; and said link being provided with a keeper for resisting its movement in the direction to release the door.

90 9. In combination with a dump car and its cargo discharging door, a gravity actuated door supporting sling mounted upon a face of the car with freedom to swing perpendicularly to said face into and out of engagement with the door, and releasable means engaging the sling below its swinging axis and opposing the swinging of the sling when in engagement with the door.

95 10. In combination with a dump car and its cargo discharging door, a gravity actuated door supporting sling mounted upon a face of the car with freedom to swing perpendicularly to said face into and out of engagement with the door, and releasable means opposing the swinging of the sling when in engagement with the door, comprising a keeper mounted with movement in a path intersecting the swinging path of the sling.

110 Signed at Chicago, Illinois, this 18th day of March, 1921.

FREDERICK S. GALLAGHER.
